UNITED STATES PATENT OFFICE.

FRANK J. SEABOLT, OF SCHENECTADY, NEW YORK, ASSIGNOR TO GENERAL ELECTRIC COMPANY, A CORPORATION OF NEW YORK.

STARTING AND SPEED-REGULATING RHEOSTAT.

1,000,848.

Specification of Letters Patent. Patented Aug. 15, 1911.

Application filed January 24, 1910. Serial No. 539,648.

To all whom it may concern:

Be it known that I, FRANK J. SEABOLT, a citizen of the United States, residing at Schenectady, county of Schenectady, State 5 of New York, have invented certain new and useful Improvements in Starting and Speed-Regulating Rheostats, of which the following is a specification.

My invention relates to devices for controlling electric motor circuits and has for 10 its object the provision of a device of this character in which the starting and speed regulation of the motor may be accomplished in a simple and efficient manner.

15 In carrying out my invention I provide, in connection with the starting and speed regulating resistances, a single controlling arm adapted to vary both of said resistances so as to accomplish both the starting and 20 speed regulation of the motor. The arrangement is such that the arm moves freely to start the motor, but has a ratchet movement when the regulating position is reached, so that the arm may be positively 25 held in any desired position. The contacts of the starting resistance are arranged in a row parallel to those of the regulating resistance and adjacent thereto, and the controlling arm is arranged to engage both 30 rows of contacts simultaneously. Means are provided whereby one resistance is short circuited while the other is being varied, so that while the motor is being started the field resistance is short circuited and while 35 the speed is being varied the starting resistance is short circuited. A ratchet member is provided at the pivotal point of the controlling arm so that when the motor is started the pawl is moved into engagement 40 with the ratchet and holds it stationary, so that the controlling arm ratchets over it, there being ratchet connection between the arm and the ratchet member itself. A no- 45 voltage magnet is provided for controlling the ratchet member so that upon failure of voltage the arm is released and permitted to return to the off position.

In the accompanying drawing in which I have shown my invention embodied in 50 concrete form for purposes of illustration, Figure 1 represents a plan view of the rheostat showing the circuit connections; and Fig. 2 is an end elevation of the mechanism.

Referring to the drawings, 10 represents

an insulating base of insulating material, 55 such as slate or soapstone, having mounted thereon two concentric rows 11 and 12 of contact studs. These studs form the terminals of resistances 13 and 14 respectively, one of which is for starting and the other 60 for speed regulation. I have shown the resistance 13 as being in series with the field of the motor for varying the field strength while the resistance 14 is intended to act as a starting resistance, although it is obvious 65 that my invention is not limited to this particular arrangement of resistances. The controlling arm 15, mounted on the pivoted pin 16, and provided with an operating handle 17, is adapted to move over and simultaneously engage studs 11 and 12. The contact 18 is secured to the under side of the arm for the purpose of engaging both sets of contacts. The arm 15 is spring-pressed or biased toward the starting position 70 against the stop 19 by means of a spring 20.

Mounted upon the pivot pin 16 so as to rotate freely thereon is a ratchet wheel 21. This ratchet wheel is in ratchet engagement 80 with the arm by means of a pawl 22 which is slidably mounted on the under side of the arm and is spring-pressed into engagement with the teeth of the ratchet wheel by a spring 23. Pivoted to the base at 24 is a 85 bell crank lever 25, one end of which is in the shape of a pawl for engaging the ratchet wheel 21, while at the opposite end it forms an armature for the no-voltage magnet 26. A light spring 27 normally holds the pawl 90 end of the lever out of engagement with the ratchet wheel and a pivoted latch 28 locks the lever in the position shown in Fig. 1. In its locked position, the pawl end of the bell crank lever engages contact stud 29, 95 which completes a short circuit of the field resistance. When the lever is attracted by the no-voltage magnet it engages a contact stud 30 which completes a short circuit of the armature resistance. The end of the 100 latch 28 is curved or cam shaped at 31 so as to be engaged by a lug or projection 32 on the arm. The arrangement is such that when the controlling arm is moved to running position the latch is engaged by the 105 lug and moved so as to release the bell crank lever 25 to permit it to be attracted by the no-voltage magnet.

The arrangement of circuits and mode of operation are as follows: To start the motor the arm is moved to the right or in a clockwise direction, the parts being in the position shown in Fig. 1. In this position the armature circuit is as follows: from the positive main through the armature A, armature resistance 14, controlling arm 15, and back to the negative main. The field circuit is completed from the positive main through the field F to the stud 29, the pivotal point 24, and conductor 33 to the negative main. The field resistance is thus short circuited. The movement of the arm is now continued toward the right until running position is reached. During this movement the arm 15 moves freely on the pivot against the tension of the spring 20 and carries with it the ratchet wheel 21, so that the arm and ratchet wheel rotate as one piece. When the running position is reached, the latch 28 is tripped so as to release the bell crank lever. As soon as this happens the no-voltage magnet, which in this case is connected across the line, attracts the armature arm of the bell crank lever against the tension of the spring 27 so as to move the arm into engagement with the stud 30, while the pawl on the opposite end of the bell crank lever is moved into engagement with the ratchet wheel. This opens the short circuit on the field resistance and short circuits the armature resistance from conductor 34, stud 30, bell crank lever 25 and conductor 33 to line. The circuit of the field is now completed from the positive main to the field F, conductor 35, arm 15 and back to line. The ratchet wheel 21 is now held in fixed position and the arm 15, as it is moved back and forth over the studs 11 to vary the field resistance, ratchets over the ratchet wheel through the pawl 22. The arm will thus be positively locked in any position in which it is left and there is no danger of being accidentally moved or of being gradually shifted by being jarred. On failure of voltage the bell crank lever 25 is released, thereby releasing the ratchet wheel and allowing the arm to return to the off position. When this happens the field resistance is again short circuited and the short circuit on the armature resistance is open. All of the parts are thus in position for another operation.

It will be seen that I have provided a simple and efficient arrangement for both starting and regulating the speed of a motor in a reliable and efficient manner. While I have, in accordance with the patent statutes, shown specific means for carrying out my invention, it should be understood that I do not limit my invention to the construction or arrangement of circuits herein shown and described, since various modifications will suggest themselves to those skilled in

the art without departing from the spirit of my invention, the scope of which is set forth in the annexed claims.

What I claim as new and desire to secure by Letters Patent of the United States, is,—

1. A rheostat comprising a starting and a speed regulating resistance, a pivoted controlling arm for first starting the motor by a movement in one direction and then varying the speed by a movement in the opposite direction, a no-voltage magnet, and means controlled thereby for causing said arm to be movable with a ratchet movement when it reaches the speed-varying position.

2. A rheostat comprising a starting and a speed regulating resistance, a pivoted controlling arm biased to the starting position and movable in one direction against the bias to cut out the starting resistance, a no-voltage magnet, and means controlled thereby for removing the bias from said arm when it reaches the running position and simultaneously causing said arm to be movable with a ratchet movement in the opposite direction to regulate the speed.

3. A rheostat comprising a resistance, a controlling arm therefor biased toward off position, a member in frictional engagement with said arm and normally movable therewith, a no-voltage magnet and means controlled by said magnet and rendered operative after a predetermined variation of resistance for holding said member fixed as the arm slips over the same to vary the resistance.

4. A rheostat comprising a starting and a speed regulating resistance, a controlling arm therefor biased toward the off position, a member having a frictional engagement with said arm and normally movable therewith, a no-voltage magnet, and means controlled by said magnet and rendered operative when the arm reaches running position for holding said member fixed as the arm slips over the same to vary the resistance.

5. A starting and speed regulating rheostat comprising a pair of resistances each provided with contact studs, a controlling member biased to the off position and simultaneously engaging the same, connections whereby said member is rendered ineffective to vary one of said resistances when moved in one direction and to vary the other of said resistances when moved in the opposite direction, a no-voltage magnet, and means controlled thereby for removing the bias from said arm and simultaneously causing the same to be movable with a ratchet movement.

6. A rheostat comprising two concentric rows of contact studs connected to starting and speed regulating resistances respectively, a controlling arm therefor biased to a predetermined position and arranged to start the motor when moved in one direction

and vary the speed when moved in the opposite direction, a no-voltage magnet, and means controlled thereby for removing the bias from said arm and simultaneously causing the same to be movable with a ratchet movement when the arm reaches the limit of movement in one direction.

7. A rheostat comprising a starting and a speed regulating resistance, a pivoted controlling arm biased to a predetermined position and arranged to first start the motor and then to vary the speed, a member pivoted concentrically with said arm and in ratchet engagement therewith, a no-voltage magnet, and means controlled thereby for holding said member fixed when the motor has been started so that the arm will ratchet over the same to vary the speed.

8. A rheostat comprising two concentric

rows of contact studs connected to starting and speed regulating resistances respectively, a controlling arm therefor biased toward the off position of the starting resistance, a ratchet member pivoted concentrically with said arm and in ratchet engagement therewith, a no-voltage magnet, a pawl controlled thereby for engaging said ratchet member to hold the same, and connections whereby either the starting resistance or the speed regulating resistance is short circuited as the pawl moves into and out of engagement with said ratchet.

In witness whereof, I have hereunto set my hand this 22nd day of January, 1910.

FRANK J. SEABOLT.
